[57] CLAIM

The ornamental design for a hand shower, as shown and described.

DESCRIPTION

FIG. 1 is a perspective view of a hand shower showing my new design;
FIG. 2 is a front elevational view thereof;
FIG. 3 is a bottom plan view thereof;
FIG. 4 is a top plan view thereof; and
FIG. 5 is a side elevational view thereof.
The flexible tube is broken away in FIG. 1 to indicate indeterminate length and omitted from FIGS. 2 through 5 for convenience of illustration.
